United States Patent Office

Des. 211,288
Patented June 4, 1968

211,288

TOILET TISSUE

Lloyd D. Smith, Cincinnati, Ohio, assignor to The Procter & Gamble Company, Cincinnati, Ohio, a corporation of Ohio

Filed May 10, 1967, Ser. No. 7,059

Term of patent 14 years

(Cl. D59—2)

The single figure of the drawing is a plan view of a toilet tissue showing my new design, the unit being marked off in broken lines, which unit is repeated in a regular succession as indicated by the extensions beyond the unit boundaries.

I claim:

The ornamental design for a toilet tissue, as shown and described.
